BOOT

Charles Miller, Long Island City, N. Y.

Application February 12, 1934, Serial No. 710,809

7 Claims. (Cl. 36—45)

This invention relates to a lady's boot of the type known as a Russian boot.

It is an object of this invention to produce a boot which is suitable for ordinary street wear and which conforms neatly and comfortably to the foot and leg of the wearer.

It is a further object of this invention to produce a boot which hugs the wearer's leg firmly at the upper margin of the boot, and which at the same time may be taken off and put on the wearer quickly and with great ease.

Another object of this invention resides in the simplicity of construction, low production cost and highly stylish effect of a boot having the foregoing properties.

These and other objects of the invention will be apparent to those skilled in the art from the following description taken in connection with the accompanying drawing, in which:

20 Fig. 1 is a perspective view of a boot embodying the present invention.

Fig. 2 is a fragmentary view of the top part of the boot, part being broken away.

Fig. 3 is fragmentary view of the top of the leg 25 of the boot, the rear seam being open to show the relation of the parts.

Fig. 4 is a plan view showing how the elastic member is attached to the top of the boot.

Referring in detail to the drawing the boot 10 30 is seen to comprise a foot portion having the vamp 11, with an upwardly projecting portion 11a as shown, quarters 12, heel 13 and outsole 14. Integral with the quarters 12 is the leg portion 15. The vamp, quarters, and leg portion are preferably made of patent leather, although other suitable materials may be used.

A top band 20 having an outer layer 21 of a suitable pile fabric such as velvet, velveteen, or the like has sewed to it on the inner side thereof 40 a band 22 of elastic webbing, by the lines of stitches 23 and 24. The webbing is cut so that its length unstretched is about 20% less than the length of the layer 21. This webbing is then stretched to the length of the latter and is sewed thereto while in this condition. As a result when the tension is released on the band 22 it retracts and causes the layer 21 to assume a gathered condition as shown in the drawing. This band so prepared is now sewed to the upper periphery 45 of the boot leg by stitches 25.

Now with the vamp, quarters, leg portion and band joined together a suitably shaped unitary boot lining 30 is stitched to the top margin of the band by the stitches 31, after which the usual rear seam (not shown) is formed. The lining is made

of any suitable fabric, preferably one having a fleece finish. The assembled foot and leg portion with its attached lining is lasted, and the outsole and heel are then attached. The usual finishing operations are finally performed.

60

Having thus described my invention, I claim:

1. A Russian boot comprising in combination a foot portion, a leg portion joined thereto, a band joined to the top of said leg portion, said band being elastic, and a boot lining joined to the top 65 of said band and lasted in with said foot portion.

2. A Russian boot comprising in combination a foot portion, a leg portion joined thereto, a band joined to the top of said leg portion, said band being elastic, and a unitary boot lining joined 70 to the top of said band.

3. A Russian boot comprising in combination a foot portion, said foot portion having an upwardly extending projection at the instep thereof, a leg portion joined to said foot portion, a band joined to the top of said leg portion said band having an elastic member, and a boot lining joined to the top of said band and lasted in with said foot portion.

4. A Russian boot comprising a foot portion, 80 a leg portion extending a substantial distance above the wearer's ankle and terminating below the wearer's knee, and a wide circumferentially-elastic band having a lower peripheral edge portion secured to said leg portion, and an upper 85 peripheral edge portion terminating below the wearer's knee, said band adapted to hug the leg of the wearer below the knee, said elastic band comprising elastic webbing and a covering layer secured thereto.

90

5. A Russian boot comprising a foot portion, a leg portion extending a substantial distance above the wearer's ankle, and terminating below the wearer's knee, and a wide circumferentially-elastic band having a lower peripheral edge portion 95 secured to said leg portion, and an upper peripheral edge portion terminating below the wearer's knee, said band adapted to hug the leg of the wearer below the knee, said elastic band comprising elastic webbing and a covering layer of substantially inextensible material stitched to said elastic webbing when the latter is under tension whereby said covering layer is gathered when the tension on said webbing is released.

100

6. A Russian boot comprising a foot portion, 105 a circumferentially-continuous leg portion extending a substantial distance above the wearer's ankle and terminating below the wearer's knee, and a wide circumferentially-elastic band having a peripheral edge portion secured to said 110

2

1,978,140

leg portion, and a peripheral edge portion terminating below the wearer's knee when in raised position and adapted to hug the leg of the wearer, said band comprising elastic material and a covering layer secured thereto.

7. A Russian boot comprising a foot portion and a circumferentially-continuous leg portion having a leg opening terminating at its upper end and below the wearer's knee, and a wide circumfer-

entially-elastic band secured to said leg portion and terminating at its upper end below the wearer's knee and adapted to resiliently constrict the leg opening of the foot about the leg of the wearer, said band comprising a covering layer of gathered material which contrasts with the material of said leg portion.
